[57] CLAIM

The ornamental design for a cover for an automotive air filter housing, as shown and described.

DESCRIPTION

FIG. 1 is a top and side perspective view of a cover for an automotive air filter housing showing my new design;

FIG. 2 is a bottom plan view thereof; and

FIG. 3 is a side elevational view thereof, the sides opposite and adjacent being identical in appearance.

FIG.1

FIG.2

FIG.3
